UNITED STATES PATENT OFFICE

ANDREW B. CAMDEN, OF IDABEL, OKLAHOMA, ASSIGNOR OF ONE-HALF TO HENRY
GRADY BOSS, OF IDABEL, OKLAHOMA.

RAZOR.

1,127,182.

Specification of Letters Patent.

Patented Feb. 2, 1915.

Application filed February 9, 1914. Serial No. 817,621.

To all whom it may concern:

Be it known that I, ANDREW B. CAMDEN, a citizen of the United States, residing at Idabel, in the county of McCurtain and State of Oklahoma, have invented certain new and useful Improvements in Razors, of which the following is a specification, reference being had to the accompanying drawings.

10 This invention relates to certain improvements in razors and has relation more particularly to a device of this general character of the safety type; and the object of the invention is to provide a device of this general 15 character wherein the cutting blade is capable of endwise movement independently of the guard during the shaving stroke.

The invention consists in the details of construction and in the combination and 20 arrangement of the several parts of my improved razor whereby certain important advantages are attained and the device is rendered simpler, less expensive and otherwise more convenient and advantageous for use, 25 all as will be hereinafter more fully set forth.

The novel features of the invention will be carefully defined in the appended claims.

In order that my invention may be the 30 better understood, I will now proceed to describe the same with reference to the accompanying drawings, wherein—

Figure 1 is a view in elevation, with parts omitted and in section, of a razor constructed in accordance with an embodiment of my invention; Fig. 2 is a view somewhat similar to Fig. 1, with the device in complete assemblage; Fig. 3 is a plan view from the inside of the top plate herein included; Fig. 4 is a sectional view taken substantially on the line 4—4 of Fig. 2; Fig. 5 is a longitudinal sectional view taken at substantially the transverse center of Fig. 3; Fig. 6 is a sectional view taken on the line 6—6 of Fig. 2; Fig. 7 is a view similar to Fig. 1, but illustrating a further embodiment of my invention; Fig. 8 is a view in elevation of a razor in complete assemblage, constructed in accordance with the embodiment disclosed in Fig. 7; Fig. 9 is a view in plan of the under face of the top plate included in this latter embodiment of my invention; and Fig. 10 is a sectional view taken substantially on the line 10—10 of Fig. 8.

55 In the embodiment of my invention dis-

closed in Figs. 1 to 6, 1 denotes a conventional handle having pivotally engaged therewith in a manner similar to the ordinary type of razor, the guard member 2' the outer extremity of which being provided along its opposite longitudinal edges with the guard fingers 4, the extremities of which, as at 5, being inwardly directed on the requisite curvature. The inner or shank portion 6 of the guard member is provided with the elongated longitudinally disposed slot or opening 7, for a purpose to be herein-after more particularly referred to.

The body portion 8 of the guard member is of a length in excess of the length of the blade 9 for reasons which are believed to be self-evident and intermediate its length such body portion 8 of the guard member is provided with the alined lugs 10 disposed at predetermined distances beyond the threaded opening 11 positioned at substantially the center of the body portion 8.

The lugs 10 are adapted to be projected within an elongated slot 12 disposed longitudinally of the blade 9 at substantially the transverse center thereof whereby, as is believed to be clearly apparent, such blade is capable of endwise movement relative to the body portion 8. As herein disclosed, the blade 9 has its opposite longitudinal margins formed into cutting edges which is well known in devices of this character and to which specific arrangement I make no claim.

Coacting with the body portion 8 of the guard member 2 and serving to maintain the blade 9 in operative position is the top plate 14 of a length substantially equal to the body portion 8 of the guard member 2 and having its opposite extremities provided with the inturned flanges 15 whereby the blade 9 is substantially entirely incased when the top plate is in applied position. The top plate is provided at substantially its center with the threaded opening 16 adapted to aline with the opening 11 and in which alined openings are adapted to be engaged a suitable retaining member 17, herein disclosed as a conventional set screw. In order to maintain the top plate against rocking movement about its connection with the body portion 8, I provide such top plate with the recesses or pockets 18 adapted to accommodate the outer extremities of the lugs 10.

The inner end of the blade 9 is provided

at substantially midway thereof with the angular projection 19, herein shown as substantially T-shaped in form, with which is adapted to be coupled the operating bar 20, as indicated at 21, such bar being disposed longitudinally of the shank portion 6 of the guard member, the inner flange 15 being provided with a suitable recess or opening 22 through which the bar 20 may project. The opposite or inner extremity of the bar 20 is provided with an operating member or head 23 disposed transversely of the shank 6 of the guard member 2 and projecting beyond the opposite longitudinal edges thereof and adapted to afford a convenient means which may be engaged by the finger of a hand holding the razor and serve to impart to the blade 9 a longitudinal movement during the shaving stroke whereby it will be readily perceived that a more effective cutting action will result. As herein disclosed, it is my purpose to cause the finger to impart movement to the blade in one direction, to wit, inwardly; and in order to impart movement to the blade in the opposite or outward direction, I have coacting with the member or finger-hold 23 the expansible member 24, herein shown as a coil spring, suitably positioned within the slot or opening 7 coacting with the member 23 in a manner which is believed to be self-evident.

In the form of the invention illustrated in Figs. 7 to 10, I disclose a razor including a blade 25 having a single cutting edge and provided with a plurality of elongated slots or openings 26 through which are adapted to project the lugs 27 formed on the body portion 28 of the guard member 29, such body portion 28 being provided with the conventional fingers 30, as is believed to be self-evident. Coacting with the body portion 28 of the guard member 29 is the top plate 31 provided at its opposite extremities with the flanges 32 adapted to abut the body portion 28 and having in its inner face the pockets or cavities 33 adapted to receive the upper extremities of the lugs 27, said top plate 31 and body portion 28 being provided with the threaded openings 34 adapted to align when the parts are assembled, and with which is adapted to be engaged a clamping or retaining member 35 also disclosed herein as a set screw.

The upper or inoperative longitudinal edge of the blade 25 is provided with the upstanding inwardly directed hook member 36 adapted to be engaged by the hooked extremity 37 of the operating bar 38, the opposite or inner extremity of such bar being provided with the operating member or finger-hold 39 adapted to be moved longitudinally of the shank 40 of the guard member 29 and with which is adapted to coact the expansible member 41, herein disclosed as a coil spring, whereby movement to the blade

25 in an outward direction is accomplished in an automatic manner. As herein disclosed, the expansible member is mounted within an elongated recess or slot 42 produced in the shank 41 of the guard member and coacting with the operating member or finger-hold 39 in a manner which is also believed to be self-evident. The guard member 29 is operatively connected with the conventional handle as has been set forth 75 relative to the first embodiment of my invention herein set forth.

From the foregoing description, it is thought to be obvious that a razor constructed in accordance with my invention is of an extremely simple and comparatively inexpensive nature and is particularly well adapted for use by reason of the endwise stroke or movement which may be imparted to the razor blade independently of and during the shaving stroke proper and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A device of the character described comprising a guard member provided with a shank, said shank having an elongated opening produced therein, an operating member slidably engaged with the shank and projecting within the opening thereof, an expansible member positioned within said opening and interposed between an end thereof and the operating member, a blade coacting with the guard member and capable of movement independently thereof, an extension projecting from the blade, and a connection between said operating member and the extension of the blade whereby said independent movement may be imparted to the blade.

2. A device of the character described comprising a guard member provided with a shank, said shank having an elongated opening produced therein, an operating member slidably engaged with the shank and projecting within the opening thereof, an expansible member positioned within said opening and interposed between an end thereof and the operating member, a blade coacting with the guard member and capable of movement independently thereof, and a connection between such operating member and the blade whereby said independent movement may be imparted to the blade.

3. A device of the character described comprising a guard member provided with a shank, said shank having an elongated opening produced therein, an operating member slidably engaged with the shank

and projecting within the opening thereof, an expansible member positioned within said opening and interposed between an end thereof and the operating member, a blade 5 coacting with the guard member and capable of movement independently thereof, an extension projecting from the blade, and a rigid connection between said operating member and the extension of the blade

whereby said independent movement may 10 be imparted to the blade.

In testimony whereof I hereunto affix my signature in the presence of two witnesses.

ANDREW B. CAMDEN.
